FIG. 3.

FIG. 5.

Richard E. Stanley Sr.
INVENTOR

BY Victor J. Evans

ATTORNEY

UNITED STATES PATENT OFFICE.

RICHARD E. STANLEY, SR., OF PITTSBURGH, PENNSYLVANIA.

HEADREST.

Application filed September 12, 1928. Serial No. 305,521.

This invention relates to a head rest which is mainly designed for supporting the head of a corpse when the same is being embalmed or otherwise handled by an undertaker or the like or by a surgeon, the general object of the invention being to provide a head rest made in the form of a stand with one pair of legs made longer than the other so that the top part of the device is in an inclined position with respect to the surface on which it is placed and said top part having a recess for receiving the rear part and neck so that the head will be held in any desired position and by moving the device toward or away from the shoulders, the head can be raised or lowered.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:—

Figure 1 is a view showing the device in use.

Figure 2 is an end view of the device.

Figure 3 is a section on line 3—3 of Figure 4.

Figure 4 is a plan view.

Figure 5 is a longitudinal sectional view.

In these views, the numeral 1 indicates the body of the device which is formed with a leg 2 at each corner thereof, the rear legs being made longer than the front legs so that the top part of the device is held in an inclined position with respect to the surface on which it is placed.

Rubber tips 2' are placed on the lower ends of the legs to prevent the device marring a surface on which it is placed.

The top of the device is formed with an opening or recess 3 which extends through the front end of the device, the end part 4 at

the open end of the device being of arc shape so as to receive the neck of the corpse, as shown in Figure 1. The closed end of the opening is formed with a curved wall and an upstanding flange 5 is formed around this end and the sides of the opening, the inner walls of the flange sloping downwardly and inwardly, as shown.

Thus I have provided a head rest which is sanitary, germ-proof and which is formed of one piece so that there is nothing to get out of order or out of adjustment and the head can be given the desired elevation by simply moving the device toward or away from the shoulders. The walls of the opening are of such a shape as to firmly support the head in adjusted position and the device is of such a construction as not to interfere in any way with the operator.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A head rest of the class described comprising a stand-like member having its rear legs of greater length than its front legs, whereby the top part of the device is held in an inclined position relative to the support on which the device is placed, a recess in the top part of the device for receiving the head and neck of a subject, said recess extending through the front end of the device with a front member of arc shape to conform to the neck of the subject and an upstanding flange around the sides and rear portion of the recess having its inner wall sloping downwardly and inwardly, with the rear end of the recess of curved formation.

In testimony whereof I affix my signature.

RICHARD E. STANLEY, SR.
